(57) **CLAIM**

The ornamental design for a beverage bag, as shown and described.

DESCRIPTION

FIG. 1 is a perspective view of a first embodiment of the beverage bag showing our new design;

FIG. 2 is a perspective view of the beverage bag shown in FIG. 1 when filled with fluid;

FIG. 3 is a left side view, with the right side view being a mirror image thereof;

FIG. 4 is a left side view of the beverage bag when filled, with the right side view being a mirror image thereof;

FIG. 5 is a top view thereof;

FIG. 6 is a top view thereof when filled with fluid;

FIG. 7 is a front view thereof;

FIG. 8 is a front view thereof when filled with fluid;

FIG. 9 is a bottom view thereof;

FIG. 10 is a perspective view of a second embodiment of the beverage bag showing our new design;

FIG. 11 is a perspective view of the beverage bag shown in FIG. 10 when filled with fluid;

FIG. 12 is a left side view, with the right side view being a mirror image thereof;

FIG. 13 is a left side view of the beverage bag when filled, with the right side view being a mirror image thereof;

FIG. 14 is a top view thereof;

FIG. 15 is a top view thereof when filled with fluid;

FIG. 16 is a front view thereof;

FIG. 17 is a front view thereof when filled with fluid;
FIG. 18 is a bottom view thereof;
FIG. 19 is a perspective view of a third embodiment of the beverage bag showing our new design;
FIG. 20 is a perspective view of the beverage bag shown in FIG. 19 when filled with fluid;
FIG. 21 is a left side view, with the right side view being a mirror image thereof;
FIG. 22 is a left side view of the beverage bag when filled, with the right side view being a mirror image thereof;
FIG. 23 is a top view thereof;
FIG. 24 is a top view of thereof when filled with fluid;
FIG. 25 is a front view thereof;
FIG. 26 is a front view thereof when filled with fluid;
FIG. 27 is a bottom view thereof;

FIG. 28 is a perspective view of a fourth embodiment of the beverage bag showing our new design;
FIG. 29 is a perspective view of the beverage bag shown in FIG. 28 when filled with fluid;
FIG. 30 is a left side view, with the right side view being a mirror image thereof;
FIG. 31 is a left side view of the beverage bag when filled, with the right side view being a mirror image thereof;
FIG. 32 is a top view thereof;
FIG. 33 is a top view of thereof when filled with fluid;
FIG. 34 is a front view thereof;
FIG. 35 is a front view thereof when filled with fluid; and,
FIG. 36 is a bottom view thereof.
